CLAIM

The ornamental design for a bicycle handlebar, as shown and described.

DESCRIPTION

FIG. 1 is a perspective view of a bicycle handlebar showing my new design;

FIG. 2 is a top plan view thereof;

FIG. 3 is a right side elevation view thereof, the left side being a mirror image of that shown;

FIG. 4 is a front elevation view thereof;

FIG. 5 is a rear elevation view thereof; and

FIG. 6 is a bottom plan view thereof.

Fig. 1.

Fig. 2.

Fig. 3.
